Primary Examiner — Barbara Fox*(74) Attorney, Agent, or Firm* — Workman Nydegger(57) **CLAIM**

The ornamental design for cheese in form of a triangular pyramid, as shown and described.

DESCRIPTION

FIG. 1 is a perspective view of cheese in form of a triangular pyramid showing the new design;
 FIG. 2 is another perspective view thereof;
 FIG. 3 is another perspective view thereof;
 FIG. 4 is a front elevational view thereof;
 FIG. 5 is a rear elevational view thereof;
 FIG. 6 is a top view thereof;
 FIG. 7 is another front view thereof; and,
 FIG. 8 is a right side view thereof.

The broken lines shown in the drawings represent portions of the cheese in form of a triangular pyramid which form no part of the claimed design.
